UNITED STATES PATENT OFFICE.

EMIL F. LEWIS FRITZ, OF CHICAGO, ILLINOIS.

CLOTHESPIN.

Application filed November 23, 1922. Serial No. 602,847.

To all whom it may concern:

Be it known that I, EMIL F. LEWIS FRITZ, a citizen of the United States, and a resident of the city of Chicago, county of Cook, and State of Illinois, have invented certain new and useful Improvements in Clothespins, of which the following is a specification.

My invention relates to new and useful improvements in clothes pins, and has for its principal object the provision of an improved construction of this character which will be simple in structure and economical in manufacture.

Other objects will appear hereinafter.

The invention consists in the combinations and arrangements of parts hereinafter described and claimed.

The invention will be best understood by reference to the accompanying drawing forming a part of this specification, and in which,

Fig. 1, is an elevational view of a clothes pin embodying the invention;

Fig. 2, is a sectional view taken substantially on line 2—2 of Fig. 1, and

Fig. 3, is a sectional view taken substantially on line 3—3 of Fig. 1.

Referring to the drawing showing the preferred form of construction 10 indicates a clothes pin which in this instance is made from a suitable mold and of such material that will permit bending at the bight 11 thereof. The clothes pin comprises an enlarged head 11' having a circular opening 12' adapted to receive the clothes line and the adjacent portion of the article on the clothes line, and leg portions 12 having rounded outer surfaces as at 13 tapered inwardly and downwardly toward the extremities of the legs 12, and inner adjacent flat surfaces as at 14. The head portion 11' diminishes in thickness from the point of juncture with the leg portions 12' to a point opposite the entrance 13' to the opening 12. The purpose of this construction is to permit diverging movement of the leg portions without rupturing the bight of the clothes pin. The extremities of the legs 12 are slightly flexed upwardly as at 15 to form a mouth 16 to facilitate mounting the clothes pin to embrace the clothes line and the articles thereon. The object of tapering legs 12 as herein stated is to reinforce the clothes pin at its weakest

point which is just below the mouth portion 12.

By the construction herein set forth it will be seen that I provide a clothes pin which will be simple in structure, economical in manufacture and durable in use, having the properties of expansion, to permit mounting, when in use.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent:

1. A clothes pin of the class described comprising leg portions joined together at one end by an enlarged head having a central opening and an entrance leading to the opening, said head portion diminishing in thickness from the point of juncture with the leg portions to a point opposite the entrance of the opening.

2. A clothes pin of the class described including leg portions having rounded outer surfaces and flat inner surfaces and joined together at one end by an enlarged head, said head portion diminishing in thickness from the point of juncture with the leg portions to a point opposite the point of juncture.

3. A clothes pin of the class described including parallel leg portions having their outer surfaces tapered inwardly and rounded in cross section and having flat inner surfaces and joined together at one end by an enlarged head portion having a central opening, said head portion diminishing in thickness toward the bight of the clothes pin.

In testimony whereof I have signed my name to this specification in the presence of two subscribing witnesses.

E. F. LEWIS FRITZ.
